UNITED STATES PATENT OFFICE

ALFRED L. WILKES, OF LOS ANGELES, CALIFORNIA

CASTING MACHINE

Application filed April 30, 1928. Serial No. 273,980.

This invention has to do with a casting machine, and it is a general object of the invention to provide an improved, effective and practical machine operable to cast material at predetermined temperatures.

The machine provided by this invention is particularly suited for casting metals or alloys in cases where definite casting temperatures are important. For example, the machine is especially suited to casting gold or gold alloys such as are used in dentistry.

For the purpose of facilitating an understanding of a simple form and application of the invention, I will refer to it as it is related to the casting of gold and gold alloys for dental purposes, it being understood that such reference is not to be construed as limiting the broader principles of the invention.

In the making of gold or gold alloy parts for dental purposes it is customary to prepare a mold or impression of the part to be formed and then cast the metal into the mold. Various types of apparatus have been devised for use in making such castings, it having been found that the centrifugal type of casting machine is well suited to this class of work. The molds are usually made of plaster, the impression being formed by embedding a wax, or similar image of the object, in the plaster to be burned out after the plaster has set. Several grades of gold and different gold alloys have been developed for dental use, it having been found that different grades of gold or various gold alloys of gold have various characteristics and that some are better suited for certain purposes than others. It is also true that a given gold or gold alloy cast at different temperatures will have different characteristics, there being an ideal casting point for each particular alloy or grade of gold.

It is an object of my present invention to provide a casting machine by which castings can be made at known temperatures, thus making it possible to obtain uniform and correct castings.

It is another object of this invention to provide a casting machine of the character mentioned which is suitable for practical or general use and is simple to operate.

A further object of the invention is to provide a casting machine of the character mentioned, arranged and constructed so that the exact temperature of the molten metal can be obtained.

55

The various objects and features of my invention will be best and more fully understood from the following detailed description of a typical form and application of the invention, throughout which description I refer to the accompanying drawings, in which:

60

Fig. 1 is a side elevation of a casting machine of the centrifugal type embodying the present invention. Fig. 2 is a plan view of the machine being a view taken as indicated by line 2—2 on Fig. 1. Fig. 3 is a detailed sectional view taken as indicated by line 3—3 on Fig. 1 showing a detailed construction that may be used in carrying out the invention. Fig. 4 is an enlarged detailed sectional view taken as indicated by line 4—4 on Fig. 2. Fig. 5 is a diagrammatic view illustrating the electrical circuits included in the device.

65

My present invention provides, generally, a casting machine in which there is a cupola 10, a mold 11 in communication with the cupola to receive molten metal therefrom, a thermo couple 12 located at or in the cupola to be subject to the same heat conditions as the metal in the cupola, and an indicating instrument 13 electrically connected with the thermo couple 12.

70

In the present disclosure I have chosen to set forth a centrifugal casting machine and therefore the cupola 10 is shown mounted on an arm 14 projecting radially from a spindle or rotor 15 driven by a spring motor 16, or the like. The arm 14 and the cupola 10 with its connected parts are counter balanced by an arm 17 and a weight 18 which also serves as a handle by which the rotor 15 can be conveniently turned to wind the motor 16. The motor 16 is provided with a suitable housing which also forms a base for the entire machine.

75

In the arrangement illustrated, the rotor is controlled by a lever 19 pivotally mounted on the exterior of the motor housing. The control lever 19 is designed to cooperate with

80

85

90

95

100

a notch 20 in the periphery of a flange 21 projecting from the rotor. When the motor is wound the control lever is engaged in the notch 20 where it will remain until operated in the direction indicated by the arrow in Fig. 2. When the control lever is operated so that it is released from the notch the rotor is released and is driven by the motor.

The cupola 10 may be of any suitable formation. For instance, it may be the ordinary open type of cupola used in casting machines of this character. In the drawings I have shown the cupola as comprising a metal case 21^a provided with a lining 22 of fire clay, or the like, shaped to form a cup-like depression A for carrying the metal to be cast. The depression A of the cupola is in communication with an opening 23 in the case of the cupola, the opening 23 being provided to pass the molten metal when the machine is operated.

The mold 11 illustrated in the drawings is of a type commonly used in making castings for dental purposes and comprises a metal case 24 carrying a body 25 of plaster, or the like, in which there is a cavity or opening B for forming the metal. The cavity B in the mold is in open communication with the opening 23 in the casing of the cupola so that the molten metal passes directly from the cupola into the mold when the machine is operated. In practice the mold is formed separate from the cupola and is releasably clamped in operating position through a suitable clamping device 26.

The thermo couple 12 provided by my invention is located in or at the cupola so that it is subject to the same heat conditions as the metal in the depression A of the cupola. In the preferred form of the invention, the thermo couple 12 is located in the bottom of the depression A of the cupola and is, in fact, mounted to project into the depression A. I have coated or protected the thermo couple with a body 30 of alundum so that it is not oxidized or amalgamated with the metal in the cupola. Wires 31 and 32 extend from the thermo couple 12 through the lining 22 of the cupola. One of these wires is grounded, for instance is connected to the rotor 15, or a suitable part of the machine, so that it is grounded with the machine, while the other is maintained out of electrical connection with the other parts of the machine.

The instrument 13 provided by my invention operates to indicate the electrical condition of the circuit in which the thermo couple is connected. The indicating instrument 13 is preferably located at a point remote from the machine. With this arrangement one of the wires from the thermo couple, for instance the wire 31 which is grounded to the machine, is connected with the instrument by a wire 31^a which is connected to the machine and extends to the instrument. The

other, or insulated wire 32 from the thermo-couple, is connected to an insulated contact ring 35 mounted on the flange 21 of the rotor. A brush 36 is mounted stationary on the motor case through suitable insulation and engages the ring to establish an electrical connection therewith. A wire 32^a connects the brush 36 with the other terminal of the instrument 13.

The instrument 13 may be of any suitable construction operable to indicate the electrical condition of the circuit in which the thermo couple is connected. The instrument preferably includes an indicating hand 40 and a dial or scale 41 with which the hand cooperates to give a reading of the electrical condition of the circuit, it being preferred that the hand and scale cooperate to give such reading directly in degrees of temperature.

My present invention further provides an automatic control for the motor adapted to be set to release the motor when the metal in the cupola has reached a predetermined temperature. In the drawings I have illustrated an arrangement wherein there is an electromagnet 50 mounted on the motor case and connected with the control lever 19. The winding of the electromagnet is connected in a circuit carried by wires 51 and 52 and energized by suitable source of power, such as a battery 53. A contact device is connected in the wire 51 at the instrument 13 to be operated by the instrument. The contact device illustrated includes a body or carrier 70 of insulating material having two spaced cup depressions 71 carrying bodies or globules 72 of mercury. The carrier 70 is mounted at the scale 41 of the instrument so that the globules of mercury 72 are in the path of the indicating hand 40. The globules of mercury are connected in the line 51 so that the circuit is closed or completed through the indicating hand 40 when the hand is in contact with both globules of mercury. The carrier 70 is adjustably mounted so that the circuit may be closed at the desired predetermined point of operation of the instrument.

In the drawings I have shown the carrier mounted in a guideway 74 extending parallel with the dial 41 and I have shown a clamp nut 75 operable to set the carrier in the desired adjusted position. It will be apparent that closing of the circuit to the winding of the electromagnet by the hand 40 of the instrument bridging the spaced mercury globules, causes operation of the control lever 19 so that the motor operates the device causing the molten metal in the cupola to be thrown into the mold.

In the preferred construction, a guide or rest 80 is provided on the motor case, to clear or be out of the path of the revolving parts of the machine. The rest may be used to support or guide a torch, or the like, that may be used in melting the metal in the cupola.

Without the guide 80 an operator might have the torch in position to be struck by the moving parts of the machine when the machine automatically operates. It is to be understood, of course, that the machine can be operated by the automatic control above described or can be manually operated by the simple operation of the lever 19.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. In a casting machine a receptacle for the material to be cast, a mold to receive the material, operating means for causing the material to discharge from the receptacle to the mold, and a control for the operating means whereby it operates upon the material reaching a predetermined temperature, the control including a thermo-couple at the receptacle, an electro-magnetic unit in connection with the operating means and a contact device electrically connected to the thermo-couple and operable to cause energization of the unit.

2. In a casting machine a receptacle for the material to be cast, a mold to receive the material, operating means for causing the material to discharge from the receptacle to the mold including a motor for rotating the receptacle, and a control for the motor whereby it operates upon the material reaching a predetermined temperature, the control including, a thermo-couple at the receptacle, an electro-magnetic unit to release the motor for operation, and a contact device electrically connected with the unit upon the material reaching a predetermined temperature.

3. In a casting machine a receptacle for the material to be cast, a mold to receive the material, operating means for causing the material to discharge from the receptacle to the mold, including, a motor for rotating the receptacle, and a control for the motor whereby it operates upon the material reaching a predetermined temperature, the control including a thermo-couple, an indicating instrument electrically connected with the thermo-couple, an electro-magnetic unit to release the motor, and a contact device operated by the instrument to engage the unit.

4. In a casting machine a receptacle for the material to be cast, a mold to receive the material, operating means for causing the material to discharge from the receptacle to the mold, including, a motor, and a control for the operating means whereby it operates upon the material reaching a predetermined temperature, the control including a thermo couple, an indicating instrument electrically connected with the thermo-couple, an electro-

magnetic unit to release the motor for operation, and an adjustable contact device operated by the instrument to energize the unit.

5. In a casting machine a receptacle for the material to be cast, a mold to receive the material, operating means for causing the material to discharge from the receptacle to the mold, and a control for the operating means whereby it operates upon the material reaching a predetermined temperature, the control including an electro-magnetic unit in connection with the operating means, a thermo-couple at the receptacle, an indicating instrument in circuit with the thermo-couple, and a contact device controlling the unit and operated by the instrument.

6. In a casting machine a receptacle for the material to be cast, a mold to receive the material, operating means for causing the material to discharge from the receptacle to the mold by centrifugal action, and a control for the operating means whereby it operates upon the material reaching a predetermined temperature, including, a thermo-couple at the receptacle and an electro-magnetic unit electrically connected with the thermo-couple operable to release the operating means.

7. In a casting machine a receptacle for the material to be cast, a mold to receive the material, operating means for causing the material to discharge from the receptacle to the mold, including a spring motor operable to rotate the receptacle, and a control for the operating means whereby it operates upon the material reaching a predetermined temperature, including, a thermo-couple at the receptacle, an indicating instrument electrically connected with the thermo-couple, an electro-magnetic unit operable to release the motor, and a contact device controlling the unit and operated by the instrument.

In witness that I claim the foregoing I have hereunto subscribed my name this 24th day of April, 1928.
